THOMAS S. HOMANS, OF HEMPSTEAD, NEW YORK, ASSIGNOR TO INTERNATIONAL TYPE-SETTING MACHINE COMPANY, OF NEW YORK, N. Y., A CORPORATION OF NEW YORK.

TYPGRAPHICAL MACHINE.

1,161,803.

Specification of Letters Patent. Patented Nov. 23, 1915.

Application filed March 12, 1915. Serial No. 13,888.

To all whom it may concern:

Be it known that I, THOMAS S. HOMANS, a citizen of the United States, residing at Hempstead, in the county of Nassau and 5 State of New York, have invented new and useful Improvements in Typographical Machines, of which the following is a specification.

The present invention relates to improvements in typographical machines and more especially to those of the linotype class and of the type adapted to handle two-letter matrices adapted to be assembled at either or both of two levels to position the desired 15 letters or characters for casting.

The primary object of the invention is to provide improved means for handling such matrices whereby they can be assembled at either or both of two levels preparatory to 20 the casting operation and restored to a common level preparatory to distribution whereby greater certainty is secured in the supporting of the matrices at the proper level or levels and in the restoring of the 25 matrices to a common level, and displacement of the matrices is practically avoided.

To these and other ends, the invention consists in certain improvements, and combinations and arrangements of parts, all as 30 will be hereinafter more fully described, the novel features being pointed out particularly in the claims at the end of the specification.

In the accompanying drawing:—Figure 1 35 is a perspective view showing one embodiment of the invention applied to the first elevator of a machine of the linotype class. Fig. 2 is an elevation of the left-hand side of the upper portion of the first elevator, 40 and illustrating the manner in which the matrices are brought to a common alignment. Fig. 3 is a view of the same side of the upper portion of the first elevator showing the matrices assembled at both upper 45 and lower levels and presented to the casting mold.

Similar parts are designated by the same reference characters in the several views.

In the present instance, the invention is 50 shown applied to a typographical machine of the well known linotype class adapted to handle two-character matrices, 1 representing the top or head of the first elevator, which may be of the customary form, 55 and as is well known has a rising and fall-

ing movement to carry the assembled matrices to the casting mold and to lift the matrices to the distributing mechanism. The top or head of the elevator carries jaws which have a channel or passageway between them to receive a line of matrices. According to the present invention, the front and rear jaws 2 and 3 are permanently held in fixed relation to provide a matrix channel of constant width between them by a spacing 60 block or equivalent means 4. A bar or member 5 is fixed to the top or head of the elevator and is provided with a rearwardly projecting matrix supporting ledge or rail 6. The jaw structure composed of the jaws 70 2 and 3 and the interposed spacing member 4 is movable bodily or as a whole relatively to the stationary ledge or rail 6. In the present instance, the jaw structure is attached to the top or head of the elevator by 75 a pivot 7 or equivalent means whereby the jaws may swing bodily to carry their lower portions toward or from the matrix supporting ledge or rail 6. Means, such for example as a spring 8, is provided to normally 80 hold the jaws in coöperative relation with the stationary matrix supporting ledge or rail 6, this spring in the present instance being attached to the jaw structure at the point 9 and to the top or head of the elevator at the point 10. When the jaws are 85 in this position, as they appear in Figs. 1 and 3, they are adapted to receive a line of matrices in the channel between them, and these matrices may be assembled at either or 90 both of the upper and lower levels. The matrices M, in Fig. 3, are shown assembled at the lower level, their upper lugs or ears resting on the ledges or rails 11 and 12 of the respective jaws, while the matrices M' 95 are shown assembled at the upper level and their lower forward lugs or ears rest upon the ledge or rail 6. In Fig. 3, the line of matrices, assembled as described, is presented 100 to the casting mold 13.

According to the present invention, the matrices are fed into the elevator from the assembling mechanism at either or both of the two levels described and are in such manner presented to the casting mold. 105 However, after the cast has been made, the mold withdraws, as is usual in machines of this class, and the elevator rises to an upper position where the matrices are removed from the elevator and are distributed and 110

returned to the proper channels of the magazine. In order to properly distribute the matrices, it is necessary to first bring all the matrices in the line to a common level. According to the present invention, the matrices are brought to a common level by swinging the jaws and the line of matrices between them rearwardly or in a direction to carry the lower lugs or ears of the matrices assembled at the upper level out of engagement with the rail or ledge 6, this movement of the jaws taking place in the present instance about the pivot or axis 7. The jaws are shown in a position to bring the matrices to a common level in Fig. 2, the upper level matrices being carried out of engagement with their supporting ledge or rail being free to drop down to align with the lower level matrices. The bringing of the matrices to a common level occurs during the latter portion of the upward movement of the elevator, and any matrices which might remain at the upper level, notwithstanding the removal of the same from their supporting ledge or rail, will be pushed down to the lower level by the bar 14. In the construction shown, a lever 15 is employed to swing the jaws and the line of matrices into a position to bring the latter to a common level, this lever in the present instance being suspended to swing from the pivot 7 and is provided with an abutment, preferably in the form of an adjusting screw 16, to bear against the forward side of the jaw structure. A track 17 is suitably supported, preferably in fixed position, and is arranged to coöperate with a projection 18 on the lever 15. This track is so shaped and positioned that, as the elevator rises toward its upper position, the projection 18 on the lever 15 engages or travels along the rear side of an inclined portion 17^a of the track, the lever being thereby swung rearwardly, carrying with it the jaws, the latter being thus brought into the position shown in Fig. 2 when the elevator has nearly reached the limit of its upward movement. The final upward movement of the elevator carries the projection 18 on the lever 15 to a position above the upper end of the track 17, and the lever 15 together with the jaws will swing forwardly under the influence of the spring 8 or under the influence of the weight of the jaws, the latter being thereby restored to normal operative relation to the matrix supporting ledge or rail 6. During the next descent of the elevator, the projection 18 on the lever 15 travels along the forward side of the track 17 until it passes beyond the lower end of the track, whereupon its projection 18 swings forward, bringing it into a position to travel along the rear side of the track during the next lifting movement of the elevator, and the screw or abutment 16 is brought into

operative position. It will therefore be understood that, during the upward movement of the elevator, the elevator jaws are carried out of coöperative relation with the matrix supporting ledge or rail 6, and that during the descent of the elevator, the elevator jaws are in normal or coöperative relation with the matrix supporting rail 6. In order to return the lever 15 to operate upon the elevator jaws after its projection 18 has passed beyond the lower end of the track, a spring 19 is provided which may be fixed, for example, to the vise jaw 2, and this spring is arranged to operate upon either side of a projection 20 on the lever 15 adjacent to 75 the pivot 7. When the spring 19 acts upon one side of the projection 20, as appears in Figs. 1 and 2 and in full lines in Fig. 3, the lever 15 is held in position for proper operation to bring the matrices to a common level during each ascent of the elevator. When, however, it is desired to retain the matrices at the different levels in order, for example, to permit re-casting from such line of matrices, or in case the machine is used wholly in connection with matrices which are assembled at the lower level, the lever 15 is swung upwardly into the dotted line position shown in Fig. 3, the spring 19 then 80 acting upon the projection 20 to support the lever 15 in a position where it will be unaffected by the track 17 during the rising and falling movements of the elevator, and in that event, the jaws will remain immovable.

I claim as my invention:—

1. In a machine of the linotype class, the combination of a pair of matrix confining jaws, a rail for supporting matrices between said jaws, the jaws being bodily movable relatively to said rail to carry matrices out of engagement with said rail, and means whereby said jaws and rail are in operative relation during descent thereof and in inoperative position during ascent thereof, comprising a track, a member coöoperative with the track, and means for retaining said member in operative or inoperative relation with the track.

2. In a machine of the linotype class, the combination of an elevator, a pair of matrix confining jaws connected in fixed relation to one another, and a rail in fixed relation to the elevator for supporting matrices between said jaws, the jaws being bodily movable in a direction away from said rail to carry matrices resting thereon out of engagement with said rail.

3. In a machine of the linotype class, the combination of an elevator, a pair of matrix 125 confining jaws rigidly connected to form between them a matrix channel of fixed width, and a rail in fixed relation to the elevator for supporting matrices in said channel, the jaws being pivoted relatively to 130

the elevator to swing bodily to carry matrices out of engagement with said rail.

4. In a machine of the linotype class, in combination with the first elevator, a matrix supporting rail rigidly mounted thereon, a pair of matrix confining jaws permanently spaced apart and pivotally mounted on said elevator, and means for moving the jaws to carry the matrices out of engagement with

10 said rail.

5. In a machine of the linotype class, the combination with an elevator, of a matrix supporting rail fixed thereon, a pair of matrix confining jaws pivoted on the eleva-

tor to swing bodily in a direction laterally 15 of said rail, and means whereby the jaws are in operative relation with the rail during descent of the elevator and in inoperative position during rising movement of the elevator.

20 In testimony whereof I have hereunto set my hand in presence of two subscribing witnesses.

THOMAS S. HOMANS.
